US00D786917S

(12) **United States Design Patent** (10) **Patent No.:** **US D786,917 S**
(45) **Date of Patent:** **** May 16, 2017**

(54) **DISPLAY SCREEN OR PORTION THEREOF
WITH GRAPHICAL USER INTERFACE**

(71) Applicant: **Samsung Electronics Co., Ltd.**, Suwon-si, Gyeonggi-do (KR)

(72) Inventors: **Seongkook Hong**, Seoul (KR); **Jinwoo Choi**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/552,925**

(22) Filed: **Jan. 27, 2016**

(30) **Foreign Application Priority Data**

Sep. 2, 2015 (KR) 30-2015-0044200

(51) **LOC (10) Cl.** **14-04**

(57) **CLAIM**

The ornamental design for a display screen or portion thereof with graphical user interface, as shown and described.

DESCRIPTION

FIG. 1 is a front view of a display screen or portion thereof with graphical user interface, showing our new design in a first embodiment;

FIG. 2 is a front view of a second embodiment thereof; and, FIG. 3 is a front view of a third embodiment thereof.

The broken lines showing the display screen and portions of the graphical user interface are included for the purpose of illustrating environmental structure and form no part of the claimed design.

1 Claim, 3 Drawing Sheets
